UNITED STATES PATENT OFFICE.

GEORGE A. STACKHOUSE, OF OAKLAND, CALIFORNIA, ASSIGNOR TO PACIFIC SPRING BED COMPANY, OF BERKELEY, CALIFORNIA, A CORPORATION OF CALIFORNIA.

DAVENPORT.

1,165,030.

Specification of Letters Patent. Patented Dec. 21, 1915.

Application filed July 17, 1914. Serial No. 851,467.

To all whom it may concern:

Be it known that I, GEORGE A. STACKHOUSE, a citizen of the United States, residing at Oakland, in the county of Alameda and State of California, have invented certain new and useful Improvements in Davenports, of which the following is a specification.

The present invention relates to improvements in davenports and more particularly to a type of structure which is adapted for use as a couch, one which may be easily changed to a bed, and one which is capable of folding into a small compass for storage or shipment.

The invention consists primarily in a supporting frame structure to the opposite sides of which are hinged independent spring structures which are capable of movement to a vertical or horizontal position and carrying a locking structure for maintaining certain of said spring structures in adjusted position.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the claims may be resorted to without departing from the spirit or sacrificing any of the advantages of the invention.

To more fully comprehend the invention, reference is directed to the accompanying sheets of drawings, wherein—

Figure 1 is a view in plan of my invention. Fig. 2 is a view in end elevation, disclosing in dotted lines the spring structures in folded position. Fig. 3 is an enlarged view of the invention with one of the spring members forming a davenport seat and the other forming a back, disclosing more fully the locking means and a mattress forming the upholstery. Fig. 4 is a detail of pivotally mounting the legs on the free ends of the spring structure. Fig. 5 is a detail view of the collapsible pillow retaining means.

Referring more particularly to the several figures of the drawings, wherein like character of reference designate corresponding parts throughout the several views, the numerals 1 designate the supporting

legs of a suitable supporting frame, one of said legs being preferably positioned at each end of the spring frame structure. Each pair of supporting legs are connected by a connecting bar 2, and frame supporting standards 3 extend upwardly as continuations of the supporting legs in spaced relation to each other. Spring supporting frames A and B are pivotally supported preferably adjacent the ends of their adjacent side edges to the upper ends of the supporting standards 3, and with adjacent longitudinal side edges in spaced relation to each other. The spring supporting frames consist preferably of the longitudinal members 4, transverse connecting members 5, and end members 6, the same supporting a spring structure 7 adapted for receiving a suitable mattress 8.

Suitable supporting legs 9 are pivotally connected at their upper ends to the outer free edges of the spring supporting frames preferably in alignment with the supporting standards 3, and said legs 9 are preferably connected by a link 10 with adjacent supporting standards 3 in such a manner that the legs 9 will be folded inwardly against the underside of the spring supporting frames A and B when the same are folded upwardly and lie in a vertical position, as in Fig. 3 of the drawings.

The pivotal connection between the supporting frames, the supporting standards and supporting legs are constructed in the following manner:—Stirrups 11 connect the longitudinal side members 4 with certain of the interior longitudinal members, and between the side members of said stirrups are positioned the upper ends of the supporting standards or supporting legs, as the case may be, they being pivotally connected to the stirrups by the shank 12 of a transversely extending securing pin which extends through suitable openings in the stirrup and in the supporting standards or supporting legs. The securing pin is curved into the form of a hook at one end, as at 13, and said hook is formed at its end with a barb 14 which is adapted, when the securing pin is in position, to be inserted through an opening 15 in one side wall of the stirrup, the barb, owing to the resiliency of the material forming the structure, engaging the side wall of the opening 15, and retaining the securing pin in position. It will be appar-

ent that the securing pins may be readily removed or inserted without the aid of tools, when it is desired to assemble or dismantle the structure.

5 A locking member 16 is pivotally mounted at one end, as at 17, to each end member of the spring supporting frame B, and overhang at their free ends the side member of the adjacent spring supporting frame A, the free ends of said members being beveled on their underside, as at 18, which bevel terminates in a catch 19, and are adapted to operate over a lug or projection 20 carried by the end members of the spring 10 supporting frame A. Suitable springs 21 engaging the end member of the spring supporting frame A and passed under the lugs or projections 20, rest at their opposite ends on the upper side of the respective locking 15 members 16 and force the same downwardly 20 in contact with the side member of the spring supporting frame A over which the locking members lie.

When the spring supporting frames A 25 and B are in a position—as in Fig. 3, and it is desired to lower the supporting frame B, it is only necessary to raise the free edge of the frame A, which will lower the rear edge thereof and cause the lugs or projections 30 20 to be raised, which will in turn elevate the free ends of the locking members and disconnect the catch thereof from the rear side member of the spring supporting 35 frame A. On the release of the locking members the spring supporting frame B may be readily depressed to a position, as in Fig. 2. On the frame B being raised from a horizontal to a vertical position, the locking members ride over the rear side member 40 of the frame A and the catch 19 thereof forced by the spring into engagement with the rear side member of the frame.

Pillow guards are carried at one end of the spring structure 7, and the same consists of a one piece framework formed preferably of wire and comprising the connected top and side members 23 and 24 forming the back of the rest and the lower ends of said side members are curved inwardly, as 45 at 25, and outwardly, as at 26, and terminate in supporting members 27 extending at right angles to the side members 24. The guards are mounted on the spring structure by inserting the supporting members 27 beneath the transverse members C of the spring structure and drawing the structure to a position so that said member C will rest in the outwardly curved portion 26 of the side members 24. Suitable spring locking fingers 28 extend downwardly from the top member 23 and are curved inwardly, as at 29, at the lower ends, adapted to engage the support C at the opposite side thereof from the bent portion 26.

65 It will be apparent that the back of the

pillow rest is capable of being folded down flat on the spring structure, in which case the supporting members extend downwardly into the spring structures.

Suitable spiral springs 29' extend longitudinally of the outer side members of the spring supporting frames to prevent the bed clothing from becoming caught between the spring structure and the spring supporting frame.

70 Suitable casters 30 are carried by the lower ends of the supporting legs 1 and 9 to assist in moving the structure.

I claim:—

1. In an article of the class described, the same comprising a supporting structure, a pair of supporting frames, each hinged to said supporting structure adjacent one side edge to swing on its longitudinal axis, and each capable of pivotal movement to a horizontal or vertical position, and means for maintaining one of said frames in a vertical position when the other of said frames is in a horizontal position, said means being releasable by a movement of the other of said frames.

2. In an article of the class described, the same comprising a supporting structure, a pair of supporting frames, each hinged to said supporting structure with adjacent side edges in spaced relation to pivot on its longitudinal axis and each capable of movement to a horizontal or vertical position, and locking means carried by one of said frames and coöperating with the other of said frames for maintaining the same in their adjusted position, said locking means when the supporting frames are in horizontal position adapted to provide a connection between the said spaced frames.

3. In an article of the class described, the same comprising a pair of supporting frames, a supporting structure formed with spaced arms, a pivotal connection between said arms and said spring supporting frames, said frames being arranged in parallel spaced relation and capable of independent pivotal movement on their longitudinal axes to a horizontal or vertical position, and a locking means carried by one of said spring supporting frames and coöperating with the other of said frames for locking one of said frames in a vertical position, said locking means being releasable on the upward movement of the other of said frames.

4. In an article of the class described, comprising a supporting structure, a pair of spaced supporting members having suitable frames pivotally connected thereto and each capable of a horizontal and vertical movement, locking means for maintaining one of said members in a vertical position, said locking means when the supporting members are in a horizontal position adapt-

ed to constitute a connection between said spaced frames, to shield the raw edges of the adjacent frames.

5. The combination with a frame member, of a supporting member and a pivotal connection therebetween comprising a pivot pin, passing through both of said members and having a hooked head portion engaging one of said members adapted to lock the 10 pivot pin in place.

6. The combination with a frame member, of a supporting member, and a pivotal connection therebetween comprising a pivot pin passed through both of said members having 15 a hooked end portion, and a barb adjacent to the terminal of the hooked portion, for engaging the said frame member to hold the pin in place.

7. An article of the class described, comprising a pair of supporting frames, a supporting standard, formed with spaced arms, said supporting frames pivotally connected to said standard and capable of a movement to a horizontal or vertical position, and locking means carried by one of said supporting frames having its free end unattached but slidably engaging the upper edge of the other of said frames and freely movable thereover for locking one of said frames in 20 a vertical position, and a resilient member

adapted to engage the locking means to normally hold the free end of the same in engagement with the upper edge of the adjacent frame.

8. In an article of the class described, 35 comprising a pair of supporting frames, a supporting structure formed with spaced arms, said frames being arranged in parallel spaced relation and pivoted adjacent corresponding side edges to said arms and capable 40 of pivotal movement to a horizontal or vertical position, and spaced locking means carried by one of said supporting frames and forming a continuation thereof when the said frames are in a horizontal position, having 45 their free ends unattached to the adjacent frame but coöperating therewith for locking one of said frames in a vertical position, a resilient member carried by one of the frame members adapted to engage the 50 free end of the locking means for forcing the same downwardly into engagement with the adjacent frame.

In testimony whereof I have signed my name to this specification in the presence of 55 two subscribing witnesses.

GEORGE A. STACKHOUSE.
